7 Claims. (Cl. 307—88.5)

The invention relates to a counting chain, consisting of electronic switching units, in which the pulse inputs of all switching units with an odd number are connected to a first bus bar and the pulse inputs of all switching units with an even number are connected to a second bus bar and the input pulses are alternately led via both bus bars. Such counting chains need no delay elements, known per se, as they are necessary for a parallel control over only one bus bar and are, furthermore, not bound to a periodic control pulse sequence.

During the undisturbed condition of the counting chain only one switching unit is always in operative position. However, it may occur that this normal condition of the counting chain is disturbed, for example, by interfering pulses on the control leads or on the current-feeding leads of the switching units. Either all switching units can be in resting position or two or more switching units can assume the operative condition.

The object of the invention is to create a counting chain in which the normal condition, after interferences, is restored. This is achieved according to the invention by starting the counting chain by use of a first coincidence circuit and restoring the counting chain, after each rundown, by means of a second coincidence circuit. In a preferred embodiment the first coincidence circuit is controlled by pulses on a bus bar and by the potential at certain outlets of all switching units, and that the second coincidence circuit is controlled by pulses on a bus bar and by the potential at an output of the final switching unit.

The invention is now explained in detail with the aid of an example and the accompanying drawings, wherein:

FIG. 1 shows a counting chain with a starting, a supervision, and a control circuit in an exemplary block diagram,

FIG. 2 shows an example of a control circuit,

FIG. 3 shows an example of a switching unit,

FIG. 4 shows an example of a starting and supervising facility, and

FIG. 5 shows a pulse diagram of a counting chain of use with FIG. 1.

The counting chain shown in FIG. 1 is constructed as a closed-circuit arrangement and consists of n equal switching units Z_1-Z_n , each switching unit possessing two control inputs e (e.g. e_{11}, e_{12}), a starting input est , a restoring input er (er_1), and two outputs a (a_{11}, a_{12}). Always one of the control inputs e (e_{11}) is connected with that output a (a_{12}) of the preceding switching unit which normally provides no pulse potential, whereas the other control inputs (pulse inputs) of the switching units with odd numbers are connected to a bus bar A_3 , and the control inputs of the switching units with an even number are connected to a bus bar A_4 . The input pulses are alternately led through said bus bars. By a coincident control at both control inputs e or by control via the starting input est the switching unit can be brought from the resting position into the operating position. Thereby the potential conditions change at both outputs a . The output of each switching unit connected with the input of the following switching unit is coupled

with the restoring facility er of the preceding switching unit via a decoupling diode D_1 ($D_{11}-D_{1n}$).

A starting device St is constructed as a coincidence circuit, having two inputs x_2, y_2 , and one output a_2 . The input x_2 is connected with the bus bar A_3 , while the input y_2 is connected to the outputs $a_{12}-a_{n2}$ via the decoupling diodes $D_{21}-D_{2n}$. The output a_2 is connected to the starting input est of the first switching unit Z_1 .

A supervising facility $Ü$ is also constructed as a coincidence circuit, having two inputs x_1, y_1 and one output a_1 . The input x_1 is connected to a separate bus bar A_2 and the input y_1 to the output a_{n1} of the last switching unit Z_n , normally furnishing pulse potential, whereas the output a_1 is connected with the restoring inputs er_1-er_3 of the switching units via decoupling diodes $D_{31}-D_{33}$, except for the last switching unit Z_n .

The bus bars A_2-A_4 are fed from a control circuit S , which, in turn, is controlled for example by a pulse contact i . Pulses occur at the bus bar A_2 which are staggered by half an impulse width compared with the pulses on the bus bars A_3, A_4 .

The control circuit S may be a trigger circuit with four transistors TA_1-TA_4 , as shown in FIG. 2. In FIG. 2 AND-circuits, consisting of resistors and diodes, inserted into the base circuit, precede the transistors, and AND-circuits being connected with the first inputs (via diodes 7, 8, 11, 12) to the control lead i , and with the second inputs (via diodes 5, 6, 17, 18) being connected to the collectors of transistors TA_1, TA_2 . The transistors TA_3, TA_4 are, in addition, fed back mutually and directly via diodes 19, 20, and connected on the collector end via the diodes 9, 10, in a certain way with the AND-circuits preceding the transistors TA_1, TA_2 .

It is assumed that the trigger circuit is in such a condition that the transistors TA_1, TA_3 are conductive (hatched on the drawing) and the transistors TA_2, TA_4 are cut-off, as the pulse diagram of FIG. 5 shows in the columns i and A_1 to A_4 . A line means that the transistor is conductive and the collector grounded. With the commencement of the first ground impulse on the control line i the transistor TA_3 is blocked, because the diode 11 becomes conductive and the diode 17 is conductive. The transistor TA_4 immediately makes the transistor TA_4 conductive via the diode 20 and causes blocking of diode 10. By the end of the first ground impulse the diode 8 ceases to be conductive so that now negative potential reaches the base of the transistor TA_2 via the diode 2, making said transistor conductive. Transistor TA_2 immediately changes the operation of transistor TA_1 via the diode 5, because the other input of the corresponding AND-circuit was already marked through transistor TA_4 and the diode 9. At the commencement of the second ground impulse the transistors TA_3, TA_4 change their switching condition, and at the end of the second ground impulse the transistor TA_1, TA_2 do the same, as can be easily gathered from the circuit diagram. After the end of the second ground impulse the aforescribed original position of the trigger circuit is reached again. Thereby pulses are produced at the bus bar A_2 which are staggered by half a pulse width compared with those at the bus bars A_3, A_4 .

The switching units Z_1-Z_n may be bistable trigger stages with two transistors T_1, T_2 per unit according to FIG. 3. The normally conductive transistor T_1 is controlled at the control inputs e_{11}, e_{12} via an AND-circuit or directly at the starting input est , whereas the normally cut-off transistor T_2 can again be brought into normal condition after reversing via the restoring input er_1 . The output a_{11} is connected with the collector of transistor T_1 and the output a_{12} with the collector of transistor T_2 .

A coincidence circuit with a transistor T having a

grounded emitter circuit can be used a starting and supervision facility, according to FIG. 4. The transistor T is conductive, if no ground potential is applied to both inputs or to one input x, y. Both inputs x, y are connected with a point of the base voltage divider through diodes and represent the inputs of an inverted AND-circuit. The collector of transistor T is the output a of said AND-circuit and has ground potential, if both inputs x, y have no ground potential.

The mode of action of the closed-circuit arrangement is now explained with the aid of the pulse diagram in FIG. 5. Beside the ground pulses on the control lead i and the bus bars A1-A4 pulses are shown on all outputs of the switching units Z1-Zn and the outputs of the starting and supervising facility St, Ü. The starting process is more specifically represented in the right upper part of FIG. 5 (up to the dotted line) than the processes in the remaining part of the drawing. In the right upper part a thick line indicates the transistor as conductive and a small line shows the transistor in its transition, a line in the remaining part of the diagram indicates the conductive condition of said transistor.

The switching units Z1-Zn are all shown in non-operative condition in FIG. 1. The outputs a11-an1 have ground potential, whereas no ground potential (but negative potential) is applied to the outputs a12-an2. The closed-circuit arrangement therefore is in a troubled condition. The pulses on the bus bars A3, A4 cannot advance the closed-circuit arrangement, because for none of the switching units is coincidence obtained at the control inputs e (e11, e12).

The starting process is initiated when the bus bar A3 has no more ground potential at the commencement of impulse 1. At that moment the inputs x2, y2 are free from ground potential, whereas the output a2 furnishes ground potential and brings the switching unit Z1 into the operative condition via the starting input est. At the outputs a11, a12 the potential conditions change. As soon as a ground impulse occurs at the output a12 the starting device St is restored again via the diode D21 and the control input e21 of the switching unit Z2 is operated, the other control input e22 is operated by the ground impulse on the bus bar A4. The ground impulse applied to the output a21 thereby ceases. The ground impulse at output a22 commences and restores the switching unit Z1 via the diode D12. With the commencement of the impulse 2 and the ground impulse applied to the bus bar A3 the switching unit Z3 is reverted which in turn restores the switching unit Z2, and so forth.

It is now assumed that the closed-circuit arrangement is in the other troubled condition in which two or more switching units are in the operative condition. When the arrangement has run down to the last switching unit Zn so that the output an1 has no more ground potential (commencement of impulse 3 or 7) ground potential is neither applied to the input y1 nor to the input x1 of the supervising facility Ü.

Therefore a ground impulse occurs at the output a1 which restores the switching units Z1-Z3 preceding the switching unit Zn. This ground impulse is terminated at the time of commencement of the ground impulse applied to the bus bar A2.

The ground restoring impulse is terminated automatically with the aid of the impulse applied to the bus bar A2 so that subsequent output pulses on the switching unit Zn and on the switching unit Z1 are not disturbed. It is possible to omit the bus bar A2 and to connect the in-

put x1 for example with the bus bar A3. With the commencement of impulse 4 and the ground impulse to the bus bar A3 the supervising facility must first be restored, before an impulse can appear at the output a12. The shortening of said impulse is in some cases without disadvantage.

The counting chain only consists of statically operating and coupled switching elements and is less subject to troubles, compared with dynamic counting arrangements. Together with the measures according to the invention a high degree of operation security is obtained.

I claim:

1. An electronic counting chain comprising two groups of units arranged in a sequence such that individual units in one group alternate with individual units in the other group, a first bus coupled to the inputs of each unit in a first group of said units and to one input of a first AND gate, a second bus coupled to the outputs of each unit in said first group and another input of said first AND gate, a third bus coupled to the inputs of each unit in the other group of said units, means for applying drive pulses to said first and third busses alternately, a second AND gate coupled to the output of a terminating one of said units, means responsive to an output from said first AND gate for starting said counting chain, and means responsive to an output from said second AND gate for resetting said counting chain, whereby said one unit is made an end of a count cycle or terminating unit.

2. The counting chain of claim 1 wherein said first AND gate has an inverted output, decoupling diode means connected between said second bus and each of said unit outputs, said last named outputs being normally "off," and means for coupling the output of said first AND gate to a starting terminal on a first of said units.

3. The counting chain of claim 1 wherein said second AND gate has an inverted output, the input to said second AND gate being coupled to a normally "on" output of the last unit in said sequence of units, the output of said second AND gate being coupled to the reset terminal of all of said units except said terminating unit.

4. The counting chain of claim 3 and means for applying signal pulses to one input of said second AND gate a half-pulse width later than said drive pulses.

5. The counting chain of claim 4 and a trigger circuit for applying said drive and signal pulses, said trigger circuit comprising four transistors coupled in a double flip-flop configuration.

6. The counting chain of claim 2 wherein each of said AND gates comprises a transistor in a common emitter configuration with diode AND gate connections to its base electrode.

7. The counting chain of claim 1 wherein each of said units comprises a multivibrator circuit of transistors in a common emitter configuration, having diode isolated inputs coupled to the base electrodes of one transistor in said multivibrator circuit.
